DESIGN FOR A DOLL

Bertha Wagner, Rye, N. Y.

Application April 19, 1947, Serial No. 138,490

Term of patent 7 years

(Cl. D34—4)

To all whom it may concern:

Be it known that I, Bertha Wagner, a citizen of the United States of America, and resident of Rye, county of Westchester, and State of New York, have invented a new, original, and ornamental Design for a Doll, of which the following is a specification, reference being had to the accompanying drawing, forming a part thereof, in which:

Fig. 1 is a front perspective view of a doll embodying my design, and

Fig. 2 is a rear perspective view thereof.

I claim:

The ornamental design for a doll, as shown.

BERTHA WAGNER.
